VACUUM CLEANER

Ernst Faber, Stuttgart, Germany

Application October 16, 1936, Serial No. 105,980
In Germany September 25, 1935

2 Claims. (Cl. 230—232)

My invention relates to vacuum cleaners and more especially to a vacuum cleaner in which the motor blower unit is yieldingly supported in an intermediate casing surrounded by the outer casing.

It is an object of my invention to provide a vacuum cleaner of the kind above defined, in which the sound is deadened more efficiently than in the vacuum cleaners hitherto suggested.

According to the present invention I provide an inner casing surrounding the motor blower unit, which is yieldingly arranged in the intermediate casing in such manner that the air current produced by the blower flows through the motor and after having left the casing surrounding the motor blower unit, flows forwardly in the intermediate casing, and, after having escaped from it, flows in rearward direction in the outer casing until it escapes into the free air. This arrangement in combination with the particularly efficient cooling effect which acts on the motor simultaneously from within and from without, results in a very efficient deadening of sound which is due not only to the double yielding support of the motor blower unit, but quite particularly to the circumstance that the air in passing through the vacuum cleaner is imparted twice a reversal of direction while being repeatedly forced to pass through a reduced cross-sectional area of passage and being alternately banked up and expanded.

I may still further improve the deadening of sound by providing a baffle covering the air exhaust opening in the intermediate casing and preventing the air from impinging directly against the outer casing.

In the drawing affixed to this specification and forming part thereof a vacuum cleaner embodying my invention is illustrated in diagrammatic axial section by way of example.

In the drawing:

a is the outer casing, *b* is the motor and *c* is the fan mounted on the motor shaft, these parts being enclosed in a unitary casing *d*, *e*, the part *d* of which has an air inlet *f* in its front wall, while the part *e* is formed with air exhaust

openings *g* near its rear wall. The motor blower unit surrounded by the casing *d*, *e* is supported by means of a rubber ring *h* at one end and a rubber ring *i* at the other end in an intermediate casing *k*, which is formed with air intakes *m* in its front wall and air exhaust openings *n* in its side wall, being yieldingly supported at either end in the outer casing *a*. To provide for such yielding supports, springs *o* extend from one end of the intermediate casing *k*, pulling this casing together with the motor blower unit towards a rubber ring *p* which abuts against the outer casing *a*.

The air exhaust openings *n* of the intermediate casing *k* are formed as a fine-meshed sieve, which is covered on the outside in a valve-like manner by a ring *q* made of felt, rubber or some other pliable material which is fixed to the sieve at its end adjoining the rubber ring *p* and allows the air to escape at the other end.

The direction of flow of the air is indicated by arrows.

I wish it to be understood that I do not desire to be limited to the exact details of construction shown and described for obvious modifications will occur to a person skilled in the art.

I claim:

1. In a vacuum cleaner in combination, an outer casing, a motor blower unit, an inner casing enclosing said unit and having a central air intake formed at its front end, which surrounds said blower, and an air exhaust near its rear end, an intermediate casing enclosing said inner casing, said intermediate casing being formed with an air intake at its front end and with an air exhaust in its circumferential part near its front end, and means for resiliently supporting said inner casing in said intermediate casing and said intermediate casing in said outer casing.

2. The vacuum cleaner of claim 1, in which there is mounted on the intermediate casing a baffle extending above the air exhaust formed on the circumferential part of said intermediate casing, said baffle being arranged to deflect the exhausted air rearwardly.

ERNST FABER.
